ION SOURCE

Manfred von Ardenne, Dresden-Weisser Hirsch, Germany, assignor to VEB Vakumosik Dresden, Dresden, Germany

Filed Jan. 24, 1956, Ser. No. 561,078

Claims priority, application Germany May 10, 1955

5 Claims. (Cl. 250—41.9)

The present invention relates to ion sources, and more particularly to an ion source for mass spectrometers and isotope sorting devices.

It is an object of the present invention to render convergent the ion streams produced by the ion source.

It is another object of the present invention to provide a convergent ion stream without an auxiliary magnetic field.

It is a further object of the present invention to provide an ion source to render a mass spectrometer or isotope sorting device more economical.

Other objects and advantages of the present invention will be apparent from the following detailed description thereof in connection with the accompanying drawings showing, by way of example, some embodiments of the present invention. In the drawings

Fig. 1 is a diagrammatic section of an ion source according to a first embodiment of the present invention,

Fig. 2 is on a larger scale a diagrammatic view of parts of a second embodiment of the present invention,

Fig. 3 is a diagrammatic view of an isotope sorting device according to the present invention,

Fig. 4 is a diagrammatic view, partly in section and seen at right angles to Fig. 3, of the isotope sorting device shown in Fig. 3,

Fig. 5 is a diagrammatic section of a further embodiment of an ion source according to the present invention.

Referring now to the drawings and first to Fig. 1, an ion source is shown which comprises a vessel generally denoted by 10 which is limited by cylindrical walls such as 12 consisting of metal and defining compartments such as an intermediate compartment 14. Rings 16, 18 and a cylindrical wall 20 consisting of insulating material separate, respectively, a first compartment 22 from the intermediate compartment 14 and a compartment 24 provided with a connection 26 leading to a differential vacuum pump (not shown).

The first compartment 22 is closed by a conductive end wall 28 having a conductive cylindrical part 29 and an electrically insulating part 30 which supports lead-in conductors 32 and 34 for a cathode 36. A gas supply pipe 38 connects a gas source indicated by the arrow with the first compartment 22. The lead-in conductor 32 is connected by a conductive connection 40 with the conductive end wall 28.

An intermediate electrode 42 connected with a terminal 44 is arranged in the chamber formed by the first and intermediate compartments 22 and 14. The intermediate electrode 42 is provided with a conical member 46 having a small opening 48 at the apex thereof. An anode 50 is arranged so as to form the closure of the intermediate compartment 22 and is conductively connected with a terminal 52 to which a relatively high anode potential is applied. The anode 50 is wedge-shaped in cross section and provided with a central opening 54 being aligned with the opening 48 of the conical member 46.

The wall 56 of the vessel 10 joining up with the insulating wall 20 and enclosing the compartment 24 is limited

2

by a cylindrical electrode 58 provided with a conical part 60 having a small centered opening 62 aligned with the openings 48 and 54. Behind the cylindrical electrode 58 a connection 64 leads to the main pump (not shown), 5 the inner hollow space of the cylindrical electrode 58 communicating with a main evacuated space or compartment 66 forming part of the vessel 10. The walls 68 of the main evacuated compartment 66 are connected with a terminal 70 connected in turn with a voltage source (not shown) accelerating the ions in the main compartment 66 and being grounded at 72.

The operation of this device is as follows:

The interior of the vessel 10 is subdivided into four compartments, viz. the first compartment 22 housing the cathode 36 and closed by the intermediate electrode 42 and the conical member 46 thereof, the intermediate compartment 14 limited on one side by the intermediate electrode 42 and the conical member 46 thereof and on the other side by the anode 50, the compartment 24 provided with the connection 26 leading to the differential vacuum pump (not shown), and the main compartment 66 provided with the connection 64 leading to the main pump (not shown). Within the different compartments 15 consecutively decreasing gas pressures are maintained by the gas entering through the supply pipe 38, the differential pump (not shown) connected to the compartment 24, and the main pump (not shown) connected to the main compartment 66. For instance, in the first and intermediate compartments 12 and 14 the pressure may 20 amount to 10^{-2} mm. Hg, in the compartment 24 to 5.10^{-4} mm. Hg, and in the main compartment 66 to 5.10^{-6} mm. Hg. The wall 28 of the first compartment 22, the wall 12 of the intermediate compartment 14, and the wall 56 of the compartment 24 are electrically insulated from one 25 another by the insulating members 16, 18, and 20 so that different potentials may be applied by the terminals 44, 52, and 70 to the respective walls of the compartments and to the intermediate electrode 36, the anode 50, and the cylindrical electrode 58 as set forth more in detail hereinabove. For example, a potential of about 30 $+300$ volts is applied to terminals 44 and 52, and a potential of about -20 kv. is applied to the terminal 70, all with respect to the cathode potential. With a suitable choice of series resistance, the potential at terminals 44 and 52 falls off by about 60 to 80 volts after ignition 35 of the arc.

The plasma or positive column 73 of the gas discharge set up between the cathode 36 and the anode 50 is concentrated by the narrow opening 48 of the conical member 46 of the intermediate electrode 42 and is highly concentrated at 74 in front of the opening 54 of the anode 50. Behind the opening 54 the plasma forms a cone 76 passing through the opening 62 of the conical part 60 of the cylindrical electrode 58 in which the cone 76 expands further as shown in Fig. 1.

55 A plasma having a high stability may be obtained according to the invention in different ways, for instance, by heating the cathode 36 normally and limiting the current by the space charge, or by heating the cathode 36 60 a little less and relying for the limitation of the current on saturation phenomena.

In the first case, that is limitation of the current by space charge, a kind of bubble consisting of a double layer is formed in which the electrons of the plasma coming from the neighborhood of the cathode are accelerated and focused on the opening 48. The electrons accelerated in the double layer ionize very strongly the neutral gas particles within this space and concentrate the plasma very strongly as shown at 74 in front of the ion emitting opening 54 of the anode 50, thus increasing 65 the density of the ion emission current.

In the second case, that is when the current is limited

by saturation, the electrons required for a vigorous ionization of the neutral gas are generated within the cathode drop itself. The cathode drop is increased artificially to 50-100 volts by heating the cathode 36 to a temperature below the saturation temperature, the emission density being uniform.

If desired, the intermediate electrode 42 may be connected with the anode 50 by a resistor (not shown) having a resistance value of several hundred ohms.

The electrode 58 should be so arranged with respect to the anode 50 that the opening 62 of the conical part 60 is arranged at a distance of a few millimeters from the opening 54 of the anode 50. The voltage of the voltage source (not shown) connected to the terminal 70 should preferably be between -10 and -60 kilovolts so that a high sucking gradient is achieved and, furthermore, the anode 50 should be shaped on the side turning toward the conical member 60 so that a plasma limit favorable from the ion-optical point of view is formed, the ion beam following a path having an as small as possible divergence notwithstanding the high density thereof. The geometry of the anode and the electrode 60, 58 should follow the rules laid down by Pierce in his text "Zur Electroden-Geometrie," published by Deutscher Verlag der Wissenschaften Berlin, 1956, volume 1, pages 514 to 521.

The angle included by the conical face 77 of the anode and the opposite face 78 thereof amounts preferably to 22°.

If the ion emitting opening 54 of the anode has a very small area, for instance, an area amounting to 0.1 square millimeter or less, the density of the ion emission will be observed to decline after a certain time even when the gas discharge operates in a constant manner. This is due to the fact that the ion beam produces gradually insulating condensate layers on the surfaces adjoining the emitting opening 54, said condensate layers originating from residual organic vapors which are almost always present. On these layers polarizing charges are formed which diminish the emission of ions owing to the polarity thereof. This disturbing phenomenon may be avoided according to the invention by manufacturing the anode 50 from platinum sheet metal which is heated either permanently or periodically by the braking energy of the discharging electrons or by external heating means 79. By this heating the insulating condensate layers are transformed into conductive carbon coatings which prevent the formation of the disturbing polarizing charges.

A great advantage of the described form of the discharge consists in that it assures excellent qualities of the ion source operating without guiding the electrons by a magnetic field. This fact is of particular importance for the economy of the total arrangement, when the latter is not axially symmetrical but designed as shown in Fig. 2 with slit-formed openings of the intermediate electrode, the anode provided with the emitting opening, and the collector electrode.

In the embodiment part of which is shown in Fig. 2, an intermediate electrode 116 encloses the linear cathode 105 secured to suitable current conductors 101 and 102. The intermediate electrode 116 is provided with a slit-formed opening 117 which is arranged so as to be aligned with the slit-formed opening 118 of the electrode or anode 121. The slit 118 of the electrode or anode 121 has ends 111 and 112 including with the principal plane of the electrode or anode 121 angles of, for instance, 22° so that a beam collecting geometry of the electrode or anode 121 according to Pierce's results. The suction electrode 110 is formed with a slit-formed opening 122 aligned with the slits 117 and 118. The elements 105-121 correspond to the like named elements of Fig. 1.

The incandescent cathode 105 is designed as a band or wire having a uniform density of emission. In dimensioning the slit 117 of the intermediate electrode 116 it should be borne in mind that the density of the plasma

will be the higher, the smaller the width of the slot 117 is. However, the width of the slot 117 cannot be diminished indefinitely because the ignition voltage is increased critically. Practical tests have shown that a width of the slot 117 amounting approximately to 3 millimeters yields a favorable compromise between the concentration of the plasma and the increase of the ignition voltage.

Since the ion source shown in Figs. 1 and 2 operates without a magnetic field it is an easy matter to attribute to the source such a shape of the ion emitting surface or plasma limiting layer that the ion beam 113 leaves the source at any desired direction. For example, in Fig. 2 the geometrical form of the system renders the sucked off ion beam convergent in the principal plane of the slits particularly by a suitable choice of the radii of curvature of the electrode in the main direction of the slits.

Referring now to Figs. 3 and 4 in which the vessel corresponding to the vessel 10 shown in Fig. 1 is omitted, an isotope separator is shown comprising a furnace 215 connected to a terminal 201. An emitting slot 215a is arranged in the front wall of the furnace 215 serving as the anode of the discharge. Inside the furnace 215 is arranged an intermediate electrode 216 provided with a slit and inside the intermediate electrode 216 is arranged a cathode 217 so that the assembly of the elements 215, 216, and 217 forms an ion gun. This furnace system yields a temperature on the surfaces of the cathode 217 and the intermediate electrode 216 which is so high that no condensation of the vapors is encountered on the surfaces. The ion rays produced within the furnace leave the same as a beam 202 and pass the electrode system 203 connected to the terminal 204. The beam has a diverging angle α in the plane of Fig. 3 and forms an angle in the plane of Fig. 4 half of which differs from a right angle by an angle β so that the beam 202 converges and forms a crossover 224 in the middle of the pole pieces 219 of a magnet generally denoted by 205. A diaphragm 223 is arranged between the furnace 215 and the magnet 205 and is connected with a terminal 206.

The magnet 205 is provided with a curved lateral surface 218 the purpose of which will be explained later.

After the ion beam 202 has passed the magnet 205 it passes the electrode 213 and the electrode 214 arranged laterally to the path thereof.

The beam 202 of ions enters finally a pocket generally denoted by 220 and including a compartment 225 for catching the relatively light isotope and a compartment 222 for catching the relatively heavy isotope, a knife-shaped wall 221 separating the compartments 225 and 222 from each other.

The operation of this device is as follows:

The beam 202 of the ions emitted by the slot 215a of the furnace 215 is restricted by the diaphragms 203 and 223 so that it enters the space of the separating magnet 205 with a very small cross section in one direction and is deflected so as to form the crossover 224 situated approximately at the center of the magnet 205 as shown in Fig. 4. The diaphragm 223 prevents any ions from directly impinging on the end faces of the pole pieces 219 of the magnet 205. The pole pieces 219 are approximately sector shaped and the sides thereof include an angle of approximately 60° (Fig. 3). The pole pieces 219 are relatively small so that the consumption of iron and copper for magnet 205 is relatively low and much reduced against the corresponding values of similar separating magnets known in the art which have weight of 200 tons whereas a magnet according to the invention has the total weight of about 20 tons.

Furthermore, frequently considerable difficulties are experienced in magnetic separators which are due to the flowing off of the parasitic electron currents formed by the ion beam passing through the residual gas through the ion accelerating distance of the ion source. These parasitic currents have the volt velocity of the full ion

accelerating voltage and intensities of 10-30 milliamps. Thus they cause frequently a melting of the ion source electrodes and prevent often the application of a high potential gradient along the path of the electrons. These difficulties are overcome by the electrodes 213 and 214 laterally arranged to the electron beam which suck off the parasitic electrons from the electron beam. Preferably a measuring instrument 230 is connected in series with the electrode 213 and a terminal 232, whereas the electrode 214 is directly connected to the terminal 234 from which the parasitic currents are taken off. The electrodes 213 and 214 are preferably kept at a positive potential against the potential of the beam 202 and designed with a relatively large surface so that a critical overheating of the same is avoided.

The path of the ion beam 202 is curved at 236 by the magnet 205 as shown in Fig. 3 and rendered convergent by the curved lateral surface 218 so as to focus the ion beam on the entrance slit 240 of the pocket 220 in which the relatively light isotope of the gas is separated from the relatively heavy isotope thereof in the compartments 223, 222. Preferably each compartment is connected with a measuring or counting instrument such as 242 (Fig. 4) connected in series with a battery 244. This instrument measures the relative number of ions entering the compartment with which the instrument 242 is connected.

Isotope separation is effected in accordance with Fig. 3 by means of the image of a symmetrical sector field, as is known in the art. Such arrangements have been used in mass spectrographs and mass spectrometers, for example in the Nier mass spectrometer. The isotopes are separated thereby in that the image of the emission slot is formed through the sector field in the place of the mounting. This image formation takes place at a given predetermined potential only for a certain predetermined ion mass. By changing the magnetic field strength ions of different mass can be formed as images successively in the gap.

The particular shape of the magnetic pole structure used, having an edge which is curved on one side, serves the purpose of eliminating image errors. This arrangement has been chosen in accordance with the publication of Smythe-Rumbaugh-West, Physical Review, vol. 45, page 724, (1934).

Fig. 5 shows another embodiment of the ion source. An evacuated vessel 300 consisting of metal is connected at one end wall 302 thereof with a hollow insulator 304 which carries a plurality of conductors generally denoted by 306 which are rigid enough for keeping the elements of the furnace or ion gun 308 in position. One conductor 310 is connected to the casing 312 of the furnace 308 which serves as an anode, two conductors 314 are connected to the cathode 316, and another conductor 318 is connected to the intermediate electrode 320. The design of the furnace corresponds to that of the furnace 215 shown in Fig. 3. In front of the opening 322 of the furnace 308 is arranged an electrode 324 provided with an opening 326 being aligned with the opening 322 for letting pass the beam 328 of electrons emitted by the furnace 308. The electrode 324 is electrically connected with the metal tube 300 which in turn is connected to ground by the connection 330. The connections 310, 314, and 318 connected, respectively, with the anode 312, the cathode 316, and the intermediate electrode 320 are kept at relatively high potentials. For example the connection 310 to the anode may have an accelerating potential of about 30 to 50 kv. The remaining connection 318 to the intermediate electrode 320 and the connection 314 to the cathode 316 differ by about 10 volts, and are also at about the same potential of 30 to 50 kv. The vessel 300 is provided with a connecting piece 332 leading to a pump (not shown). This device may be used with advantage in magnetic isotope separators.

In order to secure a high stability of the plasma pref-

erably a portion of the walls of the gas discharge chamber is covered with a sound absorbing material 333 which should be heat resistant. The high potentials in the vessel give rise to bursts which set up pressure waves in the plasma within the acoustic frequency range if the walls of the vessels are allowed to reflect the pressure waves back and forth. The sound absorbing materials on the walls of the vessel reduce these reflections and thereby reduce the vibrations within the plasma.

10 I have described hereinbefore preferred embodiments of an ion source and/or a magnetic isotope separator. However, I wish it to be understood that many changes, substitutions of equivalents, and modifications may be made in the embodiments shown in the drawings without departing from the spirit and gist of the invention which is defined by the claims attached hereto.

I claim:

1. In a non-magnetic ion source, in combination: a vessel containing a gas having a low pressure, means including a cathode and an anode electrode for maintaining a plasma of a gas discharge in said low pressure gas in said vessel, an intermediate electrode arranged in said vessel, said intermediate electrode having an opening constricting the cross section of said plasma of said gas discharge maintained in said vessel, said anode electrode having an ion emitting opening, means for biasing said intermediate and anode electrodes so that they serve as anodes for said gas discharge, said constricting opening of said intermediate electrode being arranged directly and immediately in front of said ion emitting opening of said anode electrode so as to constrict said plasma in the vicinity of said ion emitting opening of said electrode and electrostatic means to remove ions from the space between said openings in a direction axial to the opening.

2. In an ion source, in combination: a vessel containing a gas having a low pressure, non-magnetic means including a plurality of electrodes arranged in said vessel for maintaining an ion producing plasma of a directed gas discharge in said vessel, said electrodes being axially symmetrical and including an intermediate electrode and an anode, said intermediate electrode having means including an axially symmetrical opening constricting the cross section of said ion producing plasma of said directed gas discharge maintained in said vessel, said anode having an axially symmetrical ion emitting opening having a total effective area less than a square millimeter, said axially symmetrical opening in said intermediate electrode being arranged in the direction of said directed gas discharge directly in front of and so close to said anode to constrict said plasma in the vicinity of said ion emitting opening of said anode and electrostatic means for removing ions from the space between said openings through 55 the anode opening in a direction axial thereto.

3. In an ion source as claimed in claim 2, an ion accelerating electrode arranged in the direction of said directed gas discharge behind said anode, said accelerating electrode having an axially symmetrical opening arranged in said direction of said directed gas discharge behind said axially symmetrical opening of said anode.

4. In an ion source, in combination: a vessel containing a gas having a low pressure, means for maintaining an ion producing plasma of a gas discharge in said low pressure gas in said vessel, an intermediate electrode arranged in said vessel, said intermediate electrode having an opening constricting the cross section of said plasma of said gas discharge maintained in said vessel, and a platinum electrode arranged in said vessel, means for heating said platinum electrode to carbonize insulating layers thereon, for carbonizing insulating layers thereon when heated to an elevated temperature, said platinum electrode having an ion emitting opening, said constricting opening of said intermediate electrode being arranged directly in front of said ion emitting opening of said

75

platinum electrode so as to constrict the cross section of said plasma in the space between said intermediate electrode and of said platinum electrode.

5. In an ion source as claimed in claim 1, and means for reducing vibrations of the plasma in the acoustic frequency range including sound absorbing materials arranged on the inside of the wall of said vessel.
